UNITED STATES PATENT OFFICE.

EDWIN J. CUBLEY, OF RAVENSWOOD, ILLINOIS.

BANJO.

SPECIFICATION forming part of Letters Patent No. 394,159, dated December 11, 1888.

Application filed June 8, 1888. Serial No. 276,533. (No model.)

To all whom it may concern:

Be it known that I, EDWIN J. CUBLEY, a citizen of the United States, residing at Ravenswood, in the county of Cook and State of Illinois, have invented a certain new and useful Improvement in Banjos, of which the following is a specification.

In the construction of a perfect banjo it is particularly desirable that the rear end of the neck should set firmly and true against the hoop or rim portion of the head, and at the same time leave between the rim and the neck an accurately-defined space for the stretching or straining band that is commonly employed in connection with the tension-hooks or the like for stretching the parchment head upon the rim. It is also desirable that the neck should be held in perfect alignment with a line taken diametrically through the head and intersecting the center of a bracket employed as a bearing for the tension-hook that serves to engage and hold in place the tail-piece.

The objects of my invention are to provide simple, light, and highly-efficient means for holding the neck in perfect alignment with a line taken diametrically through the head; to stiffen the rim without materially increasing the weight of the head; to insure a perfect circular form of the rim; to provide improved means for holding the aforesaid tension-hook bracket in rigid connection with the rim, and to provide certain novel and improved details serving to increase the efficiency of the banjo as a musical instrument.

In a banjo characterized by my improvement the neck abuts at one end against the rim and is engaged by a rod which extends diametrically across the space within the head and at one end extends through the rim, so that it may enter the neck to a suitable extent. As a means for holding the rod in rigid connection with the rim, the latter is clamped between two jaws or shoulders upon the rod, one of said jaws being afforded by the end of the neck that abuts against the outer side of the rim, while the remaining oppositely-arranged jaw is formed by a nut, which is adjustably held upon a threaded portion of the rod and tightened up against the inner side of the rim.

In the drawings, Figure 1 represents a sec-

tion taken centrally through the head and a portion of the neck of a banjo with my improvement applied thereto, a portion only of 55 the rod C being, however, shown in longitudinal section. Fig. 2 is a bottom plan view of the banjo-head and a portion of its neck. Fig. 3 represents, on a larger scale, a section through the nut. Fig. 4 represents in elevation a portion of the head. Fig. 5 represents one of the brackets.

In said drawings, A denotes the portion of a banjo which is commonly termed the "head," and B indicates the neck, which is understood to be provided at one end with pegs for tightening up the strings, as usual.

The end of the neck which is next to the head is shaped to fit snugly against the outer side of the hoop or rim a, and is at its said end 70 provided with a notch or offset, which serves to provide between the rim and the end of the neck a space suitable for the band a', that is, as usual, arranged for engaging and holding upon the rim the parchment a'.

The metal rod C extends diametrically across the circular space within the banjo-head, and is at one end threaded and extended through and beyond the rim, so that it may enter and engage in a suitable bearing 80 in the neck, which will be properly bored to permit such connection to be made between the rod and the neck. The feature of the rod thus extending across the head and held in engagement with the neck serves as an auxiliary to the bearing of the end of the neck against the rim, in holding the neck against independent lateral vibration, and in maintaining the neck in alignment with a line taken diametrically across the space within the head. 90

As a means for clamping the end of the neck against the rim, so as to hold it in perfectly rigid connection therewith and prevent any and all jarring sound of the instrument, a nut, D, is applied upon the threaded portion c of 95 the rod and tightened up against the inner side of the rim, in which way the rim can be firmly clamped between the nut and the end of the neck, which latter will be drawn against the rim with a degree of force proportional to 100 the extent to which the nut is tightened up.

By the foregoing arrangement the rod may have any desired length of bearing in the neck, it being evident that by said arrangement

the rod is in effect in engagement with a bearing provided within and rigid with the neck, and hence that the rod is held in rigid connection with a pair of clamping-jaws formed by the nut and the neck, and will be in rigid connection with the rim. The neck will therefore be steadied and held against all tendency to vibrate independently of the rim, and by thus connecting one end of the rod with the rim through the medium of a pair of jaws, between which a suitable portion of the material of the rim is clamped, and further connecting the opposite end of the rod in any suitable way with the rim at a point diametrically opposite the point wherat the threaded-end portion of the rod passes through the rim, the circular shape of the rim will be insured, and, also, the rim will be properly stiffened by a comparatively-light metal rod, which adds but little to the weight of the head, and hence permits the free vibration necessary to the production of a good tone.

The end of the nut which is tightened up against the rim is rounded in correspondence with the curvature of the latter, and, as a preferred construction, the nut is made of such length that it will entirely conceal such portion of the thread of the nut as may be within the space of the head.

30 While the rod can be of about the same diameter throughout its length, it is preferably reduced in diameter back of its threaded portion, so that while the threaded portion of the rod may be made sufficiently large to permit 35 it to have a suitable extent of bearing-surface within the neck, the rod can be lightened by reducing the size of its remaining portion, which, while comparatively small, will have ample strength and rigidity.

40 In connection with a bracket, E, which affords a bearing for the tension-hook F, that is employed to engage and hold the tail-piece G, the rod C can be extended through the rim and threaded, so as to provide a bearing upon

which the bracket can be screwed and tightened up against the rim. To such end the rod is shouldered at a point back from one of its terminals, and its reduced end portion threaded and extended through and beyond the rim, so as to provide a threaded bearing, 45 c' , upon which the bracket E can be fitted. By tightening up the bracket E (which is in the nature of a nut) against the rim the latter can be firmly clamped between said bracket and the shoulder of the rod, whereby 50 the rod may at this end be also rigidly held in connection with the rim. The rod serves, therefore, to provide a simple and efficient arrangement of rigid bearing for the bracket, while the latter assists in holding the rod in 55 rigid connection with the rim. The threaded end of the rod is herein shown made solid, but it can be made hollow at said end, if desired, there being, however, but a small difference in weight between the two construc- 60 tions.

Should, from any cause whatever, the nut D work a little loose, it can be readily tightened up by a key, such as is used by banjo-players for tightening up the nuts of the tension-bolts, and hence, no matter how long the instrument may be in use, perfect rigidity between the neck and the rim can be preserved.

What I claim as my invention is—

The combination, with the rim of a banjo-head and the neck, of a rod extending across the space within the head and at one end engage a bearing in the neck, and a nut applied upon a threaded portion of the rod and adapted to be tightened against the rim, whereby 70 the latter may be clamped between the nut and the neck, substantially as and for the purpose described.

EDWIN J. CUBLEY.

Witnesses:

G. VAN ZANDT,
D. W. BUCHANAN.

It is hereby certified that in Letters Patent No. 394,159, granted December 11, 1888, upon the application of Edwin J. Cubley, of Ravenswood, Illinois, for an improvement in "Banjos," an error appears in the printed specification requiring the following correction, viz: In lines 77-78, page 2, the word "engage" should read *engaging*; and that the said Letters Patent should be read with this correction therein to make it conform to the record of the case in the Patent Office.

Signed, countersigned, and sealed this 25th day of December, A. D. 1888.

[SEAL.]

H. L. MULDROW,
First Assistant Secretary of the Interior.
